ABRADING TOOL

Fred Ricks and Ernest Hope, Leicester, England,
assignors to United Shoe Machinery Corporation,
Paterson, N. J., a corporation of New Jersey

Application December 4, 1934, Serial No. 755,962
In Great Britain February 6, 1934

2 Claims. (Cl. 51—194)

This invention relates to abrading tools and is herein disclosed as embodied in a disk type of tool such as is used in buffing the shank and heel breast surfaces of shoes. In United States Letters Patent No. 2,025,125, granted December 24, 1935 upon our application, we disclosed a disk type of tool the abrasive element of which consists of a strip of abrasive sheet material molded to conform to the peripheral portion of the tool body. The abrasive element of the tool disclosed in the present application is similarly molded to conform to the periphery of the tool body. In tools of this type, wherein only the marginal portion of the tool is used, a considerable saving of 10 abrasive material results from employing a strip of abrasive material rather than a large sheet which covers the entire face of the tool.

It is an object of the present invention to provide an improved abrading tool of the character under consideration. In accordance with a feature of the invention, an inflatable ring is mounted upon the rim of a wheel-like member having a hub which is adapted for attachment to a rotary spindle, and a clamping disk is provided 25 which has a hub fitting over the hub of the wheel-like structure, to clamp a dove-tail annular tongue extending from the inflatable ring against the rim of the wheel-like structure.

With the above and other objects and features in view, the invention will now be described with reference to the accompanying drawing, and pointed out in the claims.

In the drawing,

Fig. 1 is an elevational view partly in section 35 of the improved tool in operation upon the breast surface of a shoe heel;

Fig. 2 is a bottom plan view of the tool shown in Fig. 1;

Fig. 3 is a view in radial section (drawn to a 40 larger scale) of the peripheral portion of the tool shown in Fig. 1;

Fig. 4 is a view similar to Fig. 3 but showing a modification;

Fig. 5 is a plan view of a piece of woven abrasive sheet material illustrating the direction in which a strip is cut to form an abrasive element therefrom;

Fig. 6 is an elevational view of a molding device; and

Fig. 7 is a view in perspective of a molded abrasive element ready for application to a tool such as is shown in Fig. 1.

Referring to Fig. 1, the illustrated tool is supported upon the tapered end portion of a tubular 55 spindle 101 which is driven by any suitable means.

The tool comprises a body portion in the form of a wheel 103 which is conveniently made of aluminum and which has a hub 105 in which is formed a socket for receiving the end of the spindle 101. The tool body 103 is of general discoidal form, but its central portion is somewhat convex toward the spindle 101. Slidably fitting over the hub 105 is a hub of a clamping member 107 of substantially the same diameter as the tool body 103. The periphery of the tool body 103 is recessed, and the tool body 103 and the clamping member 107 have flanges 109 and 111 respectively formed thereon. A nut 113 is threaded upon the hub 105 in abutting relation to the hub of the clamping member 107.

Mounted upon the periphery of the tool body 103 is an inflatable tubular ring 115 of rubber. The form of this ring in radial section is shown in Fig. 3. At the base of the ring there extends inwardly a dove-tail tongue 117, so shaped as to be firmly gripped between the shoulders 109 and 111. The spindle 101 has an axial passageway 119 which at its upper end is connected with any suitable source of air under pressure. A small tube 121 opens at one end into the socket of the hub 105 and at its other end extends slightly beyond the surface of the recessed peripheral portion of the tool body 103. When the inflatable ring 115 is assembled in position upon the tool body, a small opening through the tongue 117 of the ring registers with the projecting end of the tube 121 to form an air-tight joint. The ring 115 is provided with an annular air chamber 123 which communicates with the above-mentioned opening in the tongue 117. Air under pressure 20 will thus pass from the passageway 119 into the socket of the hub 105, thence through the tube 121 and the opening in the tongue 117 into the air chamber 123 to inflate the ring 115. As is shown in Fig. 3, the wall of the air chamber 123 is thinner at the peripheral portion of the ring than at its sides, in order that when air under pressure is introduced into the ring the expansion of the ring will take place diametrically rather than transversely. The ring 115 may conveniently be made by vulcanizing together two suitable pieces of rubber in a mold and, as shown in Fig. 3 a strip 125 of stout non-elastic fabric such as canvas may be introduced at the joint at the base to strengthen the ring and to prevent diametrical expansion of the tongue portion of the ring. The lines 126 (Figs. 3 and 4) represent the junction of the two pieces of rubber prior to vulcanization; after vulcanization the 25

ring 115 will be a single unit. The ring 115 may be made of a single piece of rubber vulcanized in a mold, and the strip 125 may be introduced at the base to strengthen the ring and to prevent diametrical expansion of the tongue portion of the ring. The lines 126 (Figs. 3 and 4) represent the junction of the two pieces of rubber prior to vulcanization; after vulcanization the 30 ring 115 will be a single unit. The ring 115 may be made of a single piece of rubber vulcanized in a mold, and the strip 125 may be introduced at the base to strengthen the ring and to prevent diametrical expansion of the tongue portion of the ring. The lines 126 (Figs. 3 and 4) represent the junction of the two pieces of rubber prior to vulcanization; after vulcanization the 35 ring 115 will be a single unit. The ring 115 may be made of a single piece of rubber vulcanized in a mold, and the strip 125 may be introduced at the base to strengthen the ring and to prevent diametrical expansion of the tongue portion of the ring. The lines 126 (Figs. 3 and 4) represent the junction of the two pieces of rubber prior to vulcanization; after vulcanization the 40 ring 115 will be a single unit. The ring 115 may be made of a single piece of rubber vulcanized in a mold, and the strip 125 may be introduced at the base to strengthen the ring and to prevent diametrical expansion of the tongue portion of the ring. The lines 126 (Figs. 3 and 4) represent the junction of the two pieces of rubber prior to vulcanization; after vulcanization the 45 ring 115 will be a single unit. The ring 115 may be made of a single piece of rubber vulcanized in a mold, and the strip 125 may be introduced at the base to strengthen the ring and to prevent diametrical expansion of the tongue portion of the ring. The lines 126 (Figs. 3 and 4) represent the junction of the two pieces of rubber prior to vulcanization; after vulcanization the 50 ring 115 will be a single unit. The ring 115 may be made of a single piece of rubber vulcanized in a mold, and the strip 125 may be introduced at the base to strengthen the ring and to prevent diametrical expansion of the tongue portion of the ring. The lines 126 (Figs. 3 and 4) represent the junction of the two pieces of rubber prior to vulcanization; after vulcanization the 55 ring 115 will be a single unit.

two pieces of rubber are united to form an integral ring.

As shown in Figs 1 and 2, the abrasive element of the tool consists of an annular cover 127 of abrasive sheet material. This cover, before application to the tool, is shown in Fig. 7. The cover 127 has an inherent shape which is similar to that of the periphery of the ring 115. This shape may conveniently be obtained by a molding operation which will later be described. The cover is applied to the tool when the ring 115 is in deflated condition, an overlapping end of the cover being cemented to an underlapping end. As shown at 149 in Figure 7, the abrasive material is removed from the cover at the joint to avoid undue thickness of the joint. With the abrasive cover 127 thus applied to the ring 115, inflation of the ring will cause the ring to expand diametrically and thereby hold the cover 127 firmly in place. It will be evident that not only the peripheral marginal portion 129 of the cover 127 is available for buffing or scouring, but also the portions 131 of the cover adjacent to the periphery at each side thereof. These surfaces 131 are inclined at a substantial angle to the axis of rotation of the tool.

The external diameter of the illustrated tool is substantially six inches. In Fig. 1 the tool is shown in operation upon a breast surface of a shoe S having a heel H. It will be noted that by reason of the relatively large diameter of the tool, ample clearance is provided for the spindle and for the hub of the tool.

In the shoe S, as shown in Fig. 1, the locality of the shoe bottom at the junction between the shank and the heel breast surface has a substantial radius of curvature and there is no difficulty in bringing the scouring surface of the above-described tool to bear properly upon it. In the case of shoes wherein there is a sharp angle between the heel breast surface and the shank it is convenient to employ a tool having an inflatable ring such as is shown in Fig. 4 which is more sharply wedge-shaped at its periphery to enable the abrasive element to operate upon such angular portion of the shoe.

The abrasive cover 127 is conveniently formed from a strip of woven abrasive sheet material which, as illustrated in Fig. 5, is cut on the bias from a large sheet 135. The direction of the weave of the material is indicated at 137 in Fig. 3. A strip 139 is shown as having been cut at an angle of about 30° to the weave of the fabric. After the strip 139 has been cut, it is well moistened to soften it and is then molded upon a forming member 141. As shown in Fig. 6, the forming member 141 comprises a wooden cylinder having a helical projection 143 in the nature of a large screw thread formed therearound. One

end of the damp strip 139 is secured to the helical portion 143 by any suitable means such as a pin 145, whereupon the strip is wrapped around the helical projection under tension, the strip being pulled in a more or less tangential direction, as indicated by the arrow 147. Under the influence of this tension the strip will conform itself to the surface of the helical projection. When a sufficient length of the strip has thus been wrapped along the projection the free end of the strip is secured in place by another pin and the strip is left to dry upon the former. When the band is dry and removed from the former, it will be found to be in such firmly molded condition that it retains its molded shape satisfactorily under ordinary conditions of use. The external diameter of the forming member 141 is preferably somewhat less in diameter than the cover 127 when in use. The effective opening out of the molded strip to a somewhat larger diameter tends to increase to some extent the sharpness of the angle between the side portions 131 of the strip and thus tends to cause the strip to grip the rim of the inflatable ring 115. In using a helical forming member of the type above described, any desired length of strip can be molded in a single operation.

A further improvement upon abrading tools of the type above described is disclosed and claimed in the application for Letters Patent of the United States Serial No. 755,972, filed December 4, 1934 in the name of William Roderick Barclay.

Having described the invention, what is claimed as new and desired to be secured by Letters Patent of the United States is:

1. An abrading tool comprising a wheel having a hub adapted for attachment to a rotary spindle, an inflatable tubular ring mounted upon the rim of said wheel for carrying an abrasive cover, a clamping disk having a hub which fits over the hub of said wheel, said inflatable ring having an inwardly extending annular dove-tail adapted to be clamped between the rim of said wheel and the peripheral portion of said clamping disk, and means for retaining said clamping disk in clamping position.

2. An abrading tool comprising a rotary tool body, an elastic tubular ring mounted on said tool body, said ring having within it an annular air chamber, said ring having also an annular inwardly extending tongue, means engageable with said tongue for securing said ring to said tool body, and a non-elastic reinforcing member secured within said tongue to prevent diametrical expansion of the tongue portion of the ring when the ring is inflated.
